UNITED STATES PATENT OFFICE.

GEORG FORNER, OF BERLIN, GERMANY, ASSIGNOR TO GENERAL ELECTRIC COMPANY,
A CORPORATION OF NEW YORK.

ELASTIC-FLUID TURBINE.

1,160,704.

Specification of Letters Patent. Patented Nov. 16, 1915.

Application filed June 15, 1915. Serial No. 34,198.

To all whom it may concern:

Be it known that I, GEORG FORNER, a subject of the King of Prussia, residing at Berlin, Germany, have invented certain new and useful Improvements in Elastic-Fluid Turbines, of which the following is a specification.

The present invention relates to elastic fluid turbines from which elastic fluid is extracted from an intermediate stage for industrial purposes. In such machines it has been found by tests and experiment that the efficiency is improved if the machine is operated at times when the load is light and the amount of fluid being extracted small, as a purely condensing turbine, live elastic fluid being supplied directly to the extraction conduit.

The object of the present invention is to provide an improved regulating mechanism which operates to change the machine over from extraction operation to purely condensing operation, and at the same time admits elastic fluid directly to the extraction conduit whenever the condition of operation occurs as set forth above.

For a consideration of what I believe to be novel and my invention, attention is directed to the accompanying specification and the claims appended thereto.

The drawing illustrates one form which my invention may take.

Referring to the drawing, 3 indicates an elastic fluid turbine which is supplied with operating fluid by pipe 4 and exhausts through conduit 5 to a suitable condenser, (not shown).

6 indicates a valve for regulating the supply of elastic fluid to the turbine. It may be considered as indicative of any suitable regulating mechanism, either hand operated or automatic.

7 indicates a conduit leading to any point or points of consumption for low pressure elastic fluid and 8 a regulating valve therein. It is adapted to receive fluid extracted from the intermediate stage 9 of the turbine through the extraction conduit 10 or to receive live fluid direct through the pipe 11, which leads from pipe 4. The flow of fluid from the extraction conduit 10 and from pipe 11 to the conduit 7 is controlled by valves 12 and 13 respectively. These valves are preferably arranged to be operated simultaneously and in the opposite sense, and

to this end are shown in the present instance as being fixed to a common operating stem 14. When valve 13 is closed, valve 12 is open, and vice versa. The stem 14 is connected to the piston 15 of a fluid motor 16 and has an extension 17 connected to one end of the lever 18. The other end of lever 18 is pivoted at 19 to a fixed support. The pilot valve 20 of the fluid motor 16 has its stem 21 connected at an intermediate point 60 to a floating lever 22. To one end of this floating lever is connected a suitable speed governor 23 and to the other end is connected a stem 24, which is carried by the piston 25 of a pressure responsive device. The piston 25 moves in the cylinder 26 and is exposed on one side to the pressure of the condenser by way of pipe 27 and opening 28, and to the pressure of spring 29, and on the other side to the pressure beyond the 65 overflow valve 30. It will be understood that this overflow valve operates in the usual manner, its stem 31 being connected to the piston 32 moving in cylinder 33 and subjected to the stage pressure. In the cylinder is 70 a second piston 34 with its stem 35 connected to lever 18, and between the pistons 32 and 34 is a spring 36. The pressure in the space between pistons 32 and 34 is 75 condenser pressure since such space is connected 80 with pipe 27.

Under normal conditions of operation with a substantial load on the turbine the valve 13 in pipe 11 will be closed and valve 12 in extraction conduit 10 open. The overflow valve 30 will be open to a greater or less extent depending on the distribution of elastic fluid between the extraction conduit and the low pressure end of the turbine. If now the requirement for industrial purposes becomes very great, a point will be reached where the overflow valve will be entirely closed. Or on the other hand, should the load on the turbine become less while the amount of fluid being extracted is of substantial value the overflow valve will be entirely closed. This operation is well understood in connection with the overflow valve mechanism of an extraction machine. When the overflow valve is closed, of course, the pressure beyond the overflow valve will become substantially the same as condenser pressure, so that the pressure on opposite sides of the piston 25 becomes equalized. This permits the spring 29 to force the pis- 110

ton downward which is in a direction to move the pilot valve so as to admit fluid under the piston 15 of the fluid motor and thus to close valve 13 and open valve 12 as shown 5 in the drawing. Should the demand for fluid for industrial purposes now fall off the pressure in the extraction stage 9 will build up and the overflow valve 30 will be opened. The lower side of piston 25 will 10 then be subjected to this stage pressure and will move upward lifting the valves of the pilot valve 20. This, as will be readily seen, will admit operating fluid to the upper side of piston 15, causing a reversal of the positions of valves 13 and 12, the valve 13 being opened and the valve 12 closed. Live fluid will then be admitted directly to the conduit 7 by pipe 11, and since the extraction conduit is closed off the turbine will operate 15 purely as a condensing machine. This is the condition of operation which gives the highest efficiency when the load is light and the amount of fluid required for industrial purposes is also light. It will be understood 20 that the valves 12 and 13 have but two positions, the open and the closed, and that they do not assume intermediate positions.

In accordance with the provisions of the patent statutes, I have described the principle 30 of operation of my invention, together with the apparatus which I now consider to represent the best embodiment thereof; but I desire to have it understood that the apparatus shown is only illustrative, and that 35 the invention can be carried out by other means.

What I claim as new and desire to secure by Letters Patent of the United States, is,—

1. The combination of an elastic fluid turbine, an extraction conduit connected to an 40 intermediate stage thereof, a valve in said conduit, a pipe connected to said conduit at

a point beyond said valve as regards the direction of flow for supplying high pressure elastic fluid thereto, a valve in said pipe, 45 means for simultaneously moving said valves in the opposite sense to open one and close the other, and regulating mechanism which responds to a condition of light load on the turbine and limited extraction for controlling the same means.

2. The combination of an elastic fluid turbine, an extraction conduit connected to an intermediate stage thereof, a normally open valve in said conduit, a pipe connected to 55 said conduit at a point beyond said valve as regards the direction of flow for supplying high pressure elastic fluid thereto, a normally closed valve in said pipe, and means which operates to reverse the positions of 60 said valves when the load on the turbine is light and the amount of elastic fluid being extracted is small.

3. The combination of an elastic fluid turbine having an overflow valve, a conduit for 65 conveying elastic fluid to a point of consumption, means for supplying low pressure elastic fluid from an intermediate stage of the turbine or live elastic fluid to said conduit, a valve mechanism controlling said 70 means, a fluid motor for the valve mechanism, a pilot valve for the motor, a floating lever connected at an intermediate point to the stem of the pilot valve, a speed governor connected to one end of said lever, and a 75 movable abutment connected to the other, said movable abutment being subjected on one side to a constant pressure and on the other side to the pressure beyond the overflow valve.

In witness whereof, I have hereunto set my hand this 10th day of May, 1915.

GEORG FORNER.
